E. R. FIELD

VACUUM CLEANER

Filed March 20, 1922

Inventor
Egbert R. Field

By Wm. W. and W. W. Whitemore, Attorneys.

Attorney

UNITED STATES PATENT OFFICE.

EGBERT R. FIELD, OF DETROIT, MICHIGAN, ASSIGNOR TO EUREKA VACUUM CLEANER COMPANY, OF DETROIT, MICHIGAN, A CORPORATION OF MICHIGAN.

VACUUM CLEANER.

Application filed March 20, 1922. Serial No. 545,080.

To all whom it may concern:

Be it known that I, EGBERT R. FIELD, a citizen of the United States of America, residing at Detroit, in the county of Wayne 5 and State of Michigan, have invented certain new and useful Improvements in Vacuum Cleaners, of which the following is a specification, reference being had therein to the accompanying drawings.

10 The application relates to vacuum cleaning apparatus and refers more particularly to the portable type provided with a handle and also with a suction tool directly connected to the fan casing.

15 One of the objects of the invention is: to provide a simple form of handle lock for holding the handle from rotation relative to the casing of the vacuum cleaner when the handle extends substantially horizontal 20 or parallel to the longitudinal axis of this casing.

Other objects of the invention reside in the novel features of construction and combinations and arrangements of parts as 25 more fully hereinafter set forth.

In the drawings:

Figure 1 is a side elevation of a vacuum cleaner embodying my invention;

Figure 2 is a bottom plan view thereof.

30 The vacuum cleaner has the motor casing 1, the fan casing 2, and the suction tool or nozzle 3 and is supported by the rolls 4 near opposite ends of the suction tool, and the castor wheel 5 near the rear end of the 35 motor casing 1.

For moving the vacuum cleaner over the floor, it is provided with the handle 6 which carries the dust bag 7 connected to the tangential tubular outlet 8 of the fan casing

40 2. Ordinarily, the rotative position of the handle varies when the latter is in use upon the floor, but when the vacuum cleaner is not in use, it is preferred to keep the handle in substantially vertical position. Also, 45 when the vacuum cleaner is being used in raised position, it is desirable to retain the handle substantially horizontal or parallel to the axes of the motor and fan casings. In detail, the handle has the tubular portion 9 and the bifurcated inner end portion 10, the bifurcations 11 embracing and being pivotally connected to diametrically 50 opposite sides of the forward end of the mo-

tor casing 1, as at 12. One of the bifurcations 11 has the head 13, the end of which is notched as at 14 and 15, the notches being beyond the pivot 12. 16 is a tempered resilient latch detachably secured to the rear face of the casing 2 as by means of the screws 17 and having the bead 18 opposite to the pivot 12 for alternative engagement in the notches 14 and 15 for respectively holding the handle in substantially vertical and horizontal positions. The portion of the face of the head intermediate these notches is slidable over the bead of the latch so that the intermediate positions of the handle may be varied when in use. However, the portions of the face of the head beyond these notches are not slidable over the bead so that the bead determines the extreme positions of rotative adjustment of the handle relative to the motor and fan casings. To positively hold the handle in a position substantially parallel to the axes of the motor and fan casings so that the casings cannot accidentally swing relative to the handle when the latter is supporting the former, there is the slide lock 19 mounted upon the lower side of the tubular portion 9 of the handle at the junction of the bifurcations 11 and adapted to be moved beneath the bottom of the motor casing 1 near its rear end. With this arrangement, it is seen that with the handle extending substantially parallel to the axes of the motor and fan casings and with the lock 19 extended, rotation of the handle in one direction relative to the casings is limited by the slide lock abutting the lower face of the motor casing, while rotation in the other direction is limited by the latch.

What I claim as my invention is:

1. In a vacuum cleaner, the combination with a casing, of a handle pivotally connected thereto, a latch engageable with said handle when the same is extending parallel to the longitudinal axis of said casing to prevent rotation of said handle in one direction, and a sliding lock upon said handle and engageable with the lower wall of said casing when said handle is extending parallel to the longitudinal axis of said casing to prevent rotation of said handle in the opposite direction.

2. In a vacuum cleaner, the combination

with a casing, of a handle pivotally connected thereto, a member carried by said handle and adapted to bear against the lower face of said casing when said handle is disposed parallel to the longitudinal axis of said casing for preventing rotation of said handle in one direction relative to said casing, and means engageable with said handle for preventing rotation of said handle in the opposite direction when disposed in said position.

In testimony whereof I affix my signature.

EGBERT R. FIELD.
